ATTORNEY.

UNITED STATES PATENT OFFICE

RAYMOND T. BELL, OF MILWAUKEE, WISCONSIN, ASSIGNOR TO A. O. SMITH CORPORATION, OF MILWAUKEE, WISCONSIN, A CORPORATION OF NEW YORK

RAILWAY-GRADE CROSSING

Application filed July 29, 1929. Serial No. 382,005.

This invention relates to an improved railway grade crossing wherein the street level or road bed is brought to the top level of the rails being crossed in order that vehicles 5 may easily and smoothly pass thereover.

In order to facilitate repair of the railroad bed, it has heretofore been the practice to provide railroad crossings of more or less temporary construction so that the same may 10 be readily inserted and removed from the crossing.

The railroad crossings now in common use generally comprise a wooden frame inserted between the rails having a planked surface 15 or a wooden frame between which crushed stone, gravel, or other earthy materials are packed. Such crossings soon become worn and rough so that the same must be replaced frequently.

One of the objects of the present invention is to provide a crossing which is simple and easy to construct and which will have sufficient strength to withstand heavy traffic and render long periods of satisfactory service.

A further object of the invention is to provide a crossing which may be readily and rapidly assembled to minimize the interruption of traffic due to the fabrication of the 30 crossing.

A further object of the invention is to provide a crossing built up of a minimum number of standard parts which may be manufactured in the shop and which may be 35 transported in sections and readily built up into a crossing.

A further object of the invention is to provide a railway crossing having a plurality of metallic interlocking sections.

Various other objects will become apparent from the following detailed description of the invention taken in connection with the accompanying drawings.

Referring now to the drawings:

Figure 1 illustrates the finished railway crossing.

Fig. 2 is a sectional view thereof.

Fig. 3 illustrates separate individual sections.

Fig. 4 is a top plan view of the sections and

illustrates how the same may be formed into an interlocking construction.

Figs. 5 and 6 illustrate members employed for securing the sections in assembled relation.

The invention broadly contemplates the provision of a railway crossing having a plurality of metal sections assembled in interlocking relation in order that the same may be readily inserted and removed from the 60 crossing.

Referring to the drawings, the numeral 1 indicates a pair of parallel rails secured by any suitable means to the cross ties 2 as may be customary in railroad construction.

The highway or road crossing comprises a plurality of intermediate sections 3 of sheet metal preferably of channel formation, the base portion of the channel being adapted to form the surface of the road or highway 70 crossing.

The side walls 4—4 of the channel are preferably outwardly flaring and their free ends are provided with flanges 5—5 for engaging the cross ties 2. Portions of the side walls 75 are cut away at predetermined intervals to provide slots for the reception of the flanges 5—5 and the extended portions of the side walls 4—4 of the adjacent sections, as is clearly shown in Fig. 3.

The sections 6 adjacent the rails and at the end of the railway crossing may be of special construction, as shown in Figs. 1 and 2. Such sections 6 are provided at one side with a straight vertical portion 7 having an in-turned flange 8. The other side of the sections is inclined to conform with the intermediate channel sections, and portions thereof are likewise cut out to form slots for the insertion of the flanges and side walls 90 of the adjacent intermediate sections. The sections thus provided may be readily assembled in interlocking relation to each other to form a crossing which may be readily inserted and removed from the road bed and which may be endowed with sufficient rigidity to withstand the vehicle traffic for long periods of time.

In case the crossing approaches the railroad at an angle other than a right angle, 100

the interlocking sections may be placed in staggered relation to provide the desired angle and to this end the length of the cut away portions and the legs interlocking therewith 5 may be of such dimensions as to permit the desired angle by staggering the adjacent sections as aforementioned.

The sections thus built up to form a crossing may be secured to the railroad bed or 10 cross ties 2 in any suitable manner. In the drawings, special securing elements are provided, as shown in Figs. 5 and 6. The securing members, shown in Fig. 5, comprise a base plate 9 having outwardly inclined 15 flanges 10—10 conforming to the inclined surfaces of the crossing sections. The base plate 9 is provided with an aperture through which is inserted a bolt 11, spike, or other securing means which latter is driven into 20 the cross ties 2.

Fig. 6 illustrates a securing member for securing the ends of the sections similar to that shown in Fig. 5 with the exception that the end thereof is provided with a downward- 25 ly turned flange 12 adapted to engage the end of the sections.

In lieu of having the cut away portions set opposite one another, as indicated in Figs. 3 and 4, the cut away portion on one side of 30 the base of the channel may be staggered with relation to the cut away portion on the opposite side without departing from the spirit of the invention.

Although the invention has been described 35 in connection with railway crossings, it is understood that the same may be employed to bring any street or roadbed to the level of an obstruction extending across said road or street.

Having thus described the invention, it is 40 understood that various modifications may be made within the scope of the appended claims.

I claim:

45 1. A railroad crossing comprising a plurality of sheet metal channel sections in interlocking engagement with each other.

2. A railroad crossing comprising a plurality of sheet metal channel sections, each of said sections having oppositely inclined side walls, said side walls having portions thereof cut away to permit the insertion of flanges from the adjacent sections to form an interlocking construction.

55 3. A railroad crossing comprising end sections and a plurality of inverted channel-shaped intermediate sections, each of said intermediate sections having supporting legs and having portions of the side walls cut away at predetermined intervals to permit the insertion of the legs of the next adjacent section to form an interlocking construction, and means for securing said sections in interlocking relation.

65 4. A railway crossing comprising end sec-

tions and a plurality of inverted channel-shaped intermediate sections, each of said intermediate sections having supporting legs and having portions of the side walls cut away at predetermined intervals to permit the insertion of the legs of the next adjacent section to form an interlocking construction, 70 said end sections having one straight vertical side portion and one inclined side portion, said inclined side portion having portions thereof cut away at predetermined intervals 75 to receive the legs of the next adjacent intermediate section, and means for securing said sections in interlocking relation.

5. A railway crossing comprising a plurality of interlocked sheet metal channel members, the channels thereof being inverted and having slanted interdependent side walls, a foundation for supporting said members, and wedging means disposed between said 80 members for securing the same to said foundation.

6. A railway crossing comprising a plurality of spaced tie members extending transversely of the tracks, a plurality of sheet metal channel sections arranged parallel to the tracks and in interlocking engagement with each other upon said spaced tie members, and means fastening said channel sections to said 85 tie members.

7. A railway crossing comprising a plurality of sheet metal members arranged in juxtaposition, each of said members comprising a horizontal portion forming a tread surface and a downwardly extending integral flange, and means for supporting and securing said 90 members in interlocked relation.

8. A railway crossing comprising a plurality of sheet metal members arranged in juxtaposition, each of said members comprising a tread portion having its upper surface adapted to extend flush with the upper surface of said rail and downwardly extending integral flange portions; means disposed beneath said members for supporting the same, and means for securing said members in interlocking relation and to said supporting 100 means.

In testimony whereof, I have signed my name at Milwaukee, Wisconsin, this 27th day 105 of July, 1929.

RAYMOND T. BELL.
